UNITED STATES PATENT OFFICE.

JAMES G. PITTON, OF CHICAGO, ILLINOIS.

SAFETY-RAZOR.

1,321,549.

Specification of Letters Patent.

Patented Nov. 11, 1919.

Application filed October 28, 1918. Serial No. 259,957.

To all whom it may concern:

Be it known that I, JAMES G. PITTON, a citizen of the United States, residing at Chicago, in the county of Cook and State 5 of Illinois, have invented certain new and useful Improvements in Safety-Razors, of which the following is a specification.

This invention relates in general to safety razors and has for its primary object, the 10 provision of a safety razor, which, when not in use, can be assembled into the form of an elongated cylindrical container similar in size and shape to an ordinary fountain pen and adapted to contain the necessary shaving accessories, such as extra blades, a strop- 15 ping blade-holder, shaving cream and a styptic point.

Another object of the invention is to provide a safety razor which can be easily and 20 quickly changed from its cylindrical form to the form which it assumes when ready for use; which will hold the blade firmly and at the proper angle for shaving purposes and which will be simple in construction, 25 cheap to manufacture and exceedingly compact in its assembled form so that it can be conveniently carried in one's pocket without the necessity of a box or other package, which is customarily employed to carry a 30 razor and its accessories.

For the purpose of facilitating an understanding of my invention, I have illustrated one preferred form thereof, on the accompanying drawings, from an inspection of 35 which, when considered in connection with the following description, my invention and many of its attendant advantages should be readily understood and appreciated. Referring to the drawings,

40 Figure 1 is a longitudinal view, partially in section, showing my improved razor assembled for carrying in a pocket or the like.

Figs. 2 and 3 are transverse sectional views on the lines 2—2 and 3—3 respectively of Fig. 1.

Fig. 4 is a fragmentary view, partially in section, of my razor when assembled for shaving.

Fig. 5 is a sectional view on the line 5—5 50 of Fig. 1; and

Fig. 6 is a perspective view of the strop- ping blade-holder with a blade therein.

From an inspection of the drawings and particularly Fig. 1 thereof, it will be observed that the razor comprises primarily 55 an elongated cylindrical body quite similar in appearance, when viewed externally, to an ordinary fountain pen. The body consists of a plurality of sections, in the present instance three, namely: a cap section 7, a handle section 8, and a blade section 9. These sections may be made of any preferred material such as hard rubber, metal, or other suitable material; and section 8 has a reduced threaded end 11, on to which the 60 correspondingly threaded end of section 9 is adapted to be screwed, and section 8, at its opposite end, is reduced and threaded as indicated by character 12 to accommodate the correspondingly threaded open end of 70 the cap section when assembled, as shown in Fig. 1, providing a continuous cylindrical body or container.

This sectional container is adapted to receive and carry the various shaving accessories which are ordinarily required, for instance, a small size tube of shaving cream 13 may be disposed in the section 9; strop- ping blade-holder 14 may be carried in the section 8; and extra blades 15 and a styptic 80 pencil 16 may be carried in the section 7, which may be provided with a pencil holder 17 and a partition 18, which prevents the blades from shaking around. The outer end of the section 9 is closed, and preferably 85 this closure is effected by a removable cap 19 which will not interfere with the dia- metrical contraction of this section for the purpose of clamping the blade in position, as will be fully explained. 90

It will be apparent from the drawings that the section 9 is provided with a longitudinally extending slot 21, adapted to receive a blade, the inner end of this slot being widened out as indicated in 22, to facilitate 95 the insertion of a blade longitudinally thereinto. Opposite the slot and in alinement therewith, the inner wall of the section may be, if preferred equipped with a shoulder 23 to provide a retaining abutment against 100

which the rear edge of the blade abuts. The angle of the slot 21 and the position of the abutment 23 are such that the projecting cutting edge of the blade projects at the proper angle with respect to the periphery of the section 9 to facilitate its cutting action during shaving. This position of the blade is clearly shown in Fig. 4, from which it will be seen that the blade does not project radially but assumes the position of a chord of an arc of the holding section.

After the section 9 has been detached by unscrewing and the shaving cream tube has been removed, the blade is inserted as just explained, into position in the blade-holding section whereupon the handle section 8 which has been disconnected from the cap section 7 is attached to the blade-holding section. The means for connecting the handle section and the blade-holding section together comprises coöperating devices carried by the respective sections. Section 9, as will be apparent from Figs. 4 and 5, is provided with a transversely extended opening, the upper portion consisting of an inwardly projecting boss 24, being threaded internally as indicated in 25, while the lower portion, consisting of a boss 27, is plain to permit the insertion therethrough of a stud or pin 26, projecting longitudinally from one end of section 8. This section is provided with a round, flat shoulder at the base of the pin and the outer end of the boss 26 is correspondingly flattened as indicated at 31, to provide a steady bearing surface between the sections 8 and 9. The outer end of the pin 26 is threaded, as indicated at 32, to screw into the boss 24, and when it is screwed tightly into this boss the sides of the slots 21 will be drawn toward each other to firmly clamp the blade between them, as shown in Fig. 4. The blades are each provided, intermediate their ends, with a slot 33 to receive the pin 32 whereby the blade is held against longitudinal movement in the holder and the inner end of the boss 24 is preferably cut at an angle parallel to the blade so that its inner end snugly engages the blade near its rear edge to further steady the blade in its clamped shaving position. When the parts have been assembled by insertion of the pin 26 into the section 9 and the blade has been firmly clamped in shaving position by threading this pin into the threaded boss 24, the razor is ready for use in the customary manner of all safety razors in which the blade is disposed at right angles to the handle.

In case it is desired to strop a blade, the 60 blade is inserted longitudinally into the stropping blade-holder 14, the side walls of which are made of spring metal, so as to firmly clamp the blade near its cutting edge, the rear edge of the blade being located in

a groove 34 formed in the back of the holder. 65 The handle 8 may then be attached to the holder by threading the pin 26 into a tapped extension 35 at the back of the holder whereupon the stropping operation may be performed in the usual manner.

It is believed that my invention and many of the attendant advantages will be fully understood from the foregoing without further description and it should be manifest that I have provided a razor which normally, when not in use, takes up very little room and carries all the necessary accessories within itself and that it can be quickly taken apart and reassembled for use when desired. While I have shown and described 80 one preferred embodiment of my invention, it should be manifest that various changes in the size, shape and proportion of the parts may be resorted to without departing from the spirit of the invention, as defined in the 85 following claims.

I claim:

1. A safety razor comprising a plurality of tubular sections adapted to be united to form a cylindrical container for a plurality of shaving accessories, one of said sections being provided with a blade receiving slot, and coöperating means located intermediate the ends of said section and at one end of another of said sections respectively for connecting said sections together at right angles to each other and extending through said blade to lock the blade in shaving position.

2. A safety razor comprising a plurality of tubular sections adapted to be connected 100 in longitudinal alignment to form a cylindrical container for a plurality of shaving accessories, one of said sections being provided with a longitudinally disposed blade receiving slot and a transversely disposed 105 opening, and another of said sections being provided with a longitudinal extension adapted to extend through said blade and engage in said opening to clamp the blade in said slot and secure said sections together. 110

3. A safety razor comprising a sectional tubular body adapted to provide a container for shaving accessories, means whereby one of said sections may be attached to another of said sections in transverse relation 115 thereto, and a blade adapted to be disposed in said transversely positioned section with its cutting edge projecting beyond the periphery of said section, said section serving as a guard for the cutting edge of said blade 120 and the means for securing the said sections together being adapted to lock said blade in position.

4. A safety razor comprising a blade-holding section, a blade therein, a handle 125 section, coöperating means carried by said sections one portion of which extends through said blade whereby said blade-

holding section is secured to the handle section and the blade is clamped in shaving position, said sections being adapted to be united in longitudinal alinement to form a 5 cylindrical container for shaving accessories.

5. A safety razor comprising an elongated cylindrical body consisting of three longitudinally united sections each adapted to

contain shaving accessories, one of said sections being adapted to hold a blade in 10 shaving position and serving as a safety guard for the cutting edge thereof, and means for attaching said section to the end of another of said sections and simultaneously locking said blade in position.

JAMES G. PITTON.
